UNITED STATES PATENT OFFICE

SPENCER C. WOODY, OF SEATTLE, WASHINGTON

PERIPHERAL JET PUMP

Application filed November 19, 1929. Serial No. 408,195.

The invention is an improvement in suction pumps of the peripheral jet type wherein in the outer surface of the jet nipple is conical shaped and the surrounding chamber provided with a vacuum tank connection thereby making it possible to use the device for an injector.

One object of the invention is to provide a device for discharging or ejecting fluids or substances by a fluid under pressure in which the device is so constructed that objects as large as the inlet and exhaust pipes may pass through.

Another object of the invention is to provide a suction pump having a chamber surrounding the pump in which an air cushion is formed which maintains a constant pressure through the pump.

Another object of the invention is to provide a suction pump of the character described which may be used as either an ejector or injector.

A further object of the invention is to provide a suction pump in which the pressure connection may be made at right angles to the axis of the pump.

A still further object of the invention is to provide a suction pump in which the length is reduced to a minimum.

And a still further object of the invention is to provide a suction pump in which the complete pump is contained in two parts and in which the entire pump is of a simple and economical construction.

With these ends in view the invention embodies a housing with pipe connections at the ends and a circular chamber formed on the interior thereof, a sleeve extending through the circular chamber, and an inlet connection in one side of the circular chamber.

Other features and advantages of the invention will appear from the following description taken in connection with the drawings, wherein:

Figure 1 is a vertical section through the device.

Figure 2 is a sectional plan through the central portion of the device.

In the drawings the device is shown as it

would be made wherein numeral 1 indicates the housing, numeral 2 the jet sleeve, and numeral 3 the inlet connection.

The housing 1 is made with a cylindrical portion as shown having an enlarged cylindrical chamber 4 at the lower part thereof, a boss 5 having a threaded opening 6 at the outer side of the cylindrical chamber, and a nut 7 at the opposite end.

The sleeve 2 extends through the chamber 4 and the cylindrical portion of the housing to the point 8 as shown in Figure 1. This sleeve extends from a nut 9 which screws into the boss 5, with a straight inner surface, and the outer surface is inclined outward from the point 8 at a slight angle forming a portion of a cone, and it will be observed that a suction pipe 10 may be threaded into the opposite side of the nut. A discharge pipe 11 is threaded into the opposite end of the housing as shown.

The inlet connection 3 is formed at one side of the chamber 4 and is formed with a boss 12 into which a pipe 13 is threaded. This pipe may be connected to any suitable means for supplying a fluid under pressure.

The chamber 4 may also be provided with a connection formed by a boss 14 through which it may be connected by a nipple 15 to a vacuum tank 16 when the device is used as an injector. The tank 16 may be removed and the opening in the boss 14 closed by a plug 17 when the device is used as an ejector, as shown in Figure 1.

It will be understood that changes may be made in the construction without departing from the spirit of the invention. One of which changes may be in the shape, design or arrangement of the housing, another may be in the proportionate size of the surrounding chamber, another may be in the location of the inlet connection, and still another may be in the means for holding the sleeve in the central part of the housing.

The construction will be understood from the foregoing description. In use the device may be provided as shown and it will be observed that with steam under pressure, or any fluid under pressure supplied to the pipe 13 the fluid will pass around the central part

and compress the air in the chamber 4 around the outer edge, as it will be noted that the pressure of the incoming fluid will be so much greater than that of the air and the outlet passage of such a comparatively small size 5 that the air in the chamber will be backed up and compressed in the outer part thereof or in the space indicated by the numeral 18. This will form an air cushion which will 10 maintain the fluid at a constant pressure so that the jet action will be materially facilitated. The fluid rushing through the device and passing out through the thin space between the outer surface of the sleeve 2 and the inner surface of the cylindrical portion 15 of the housing 1, will create a suction that will draw a fluid or material through the inlet connection 10 and discharge or eject it through the pipe 11. The fluid under pressure 20 around the periphery of the sleeve and escaping through a thin circular opening at one end forms a jet with a large throat opening so that it will have considerable force and at the same time be adaptable to discharge 25 bulky substances or objects substantially as large as the pipe. In order to obtain 30 this action it is necessary to locate the pressure connection 13 at the exterior of the chamber 4 and perpendicular to the axis of the pump. It will be observed that the pipe 35 10 may be inserted in practically any type of substance which may be of a liquid or gaseous consistency or may even be of a solid, such as sand or other similar freely moving 40 material. It will, therefore, be observed that as the interior of the device is open to an area equivalent to that of the inlet and discharge 45 pipes, and also as it may be used as either an injector or ejector it may be used universally for many purposes.

Having thus fully described the invention, what I claim as new and desire to secure by Letters Patent, is:

In a peripheral jet of the character described, two abutting pipe sections with a space between their ends, a casing into which one of the said sections is screwed, said casing having an enlarged circular interior opening, the large diameter of said opening being approximately three times the diameter of the said pipe sections providing space for 50 an air cushion in the outer part thereof, a plug screwed into the side of the said casing opposite to that in which the section of pipe 55 is screwed, said plug extending through the said circular opening in the said casing and a considerable distance beyond the adjacent wall thereof, the outer surface of the said 60 plug tapering outward from the end thereof, and said casing having a corresponding tapering surface over the portion of the plug that extends beyond the said adjacent wall of the opening in the said casing, the other 65 section of pipe screwed into the outer end

of the said plug and in axial alignment with the former section, said casing having a suitable inlet opening at one side connecting with the said interior opening and also having a plug at the opposite side of the said interior opening, and the area of the central continuous opening extending through the said plug and casing being not less than the area of the said pipe sections.

In testimony whereof he affixes his signature.

SPENCER C. WOODY.
